(57) **CLAIM**

We claim the ornamental design for a valve, as shown and described.

DESCRIPTION

The design application contains at least one drawing executed in color. Copies of this design application publication with color drawings will be provided by the Office upon request and payment of the necessary fee.

FIG. 1 is a perspective view from the bottom and left hand side of a valve in accordance with a first embodiment of the present invention;

FIG. 2 is a front view of the valve shown in FIG. 1, with the valve being illustrated in the closed position;

FIG. 3 is a rear view of the valve shown in FIG. 1;

FIG. 4 is a left hand side view of the valve shown in FIG. 1;

FIG. 5 is a right hand side view of the valve shown in FIG. 1;

FIG. 6 is a top view of the valve shown in FIG. 1;

FIG. 7 is a bottom view of the valve shown in FIG. 1;

FIG. 8 is the same front view of the valve as shown in FIG. 2, except with the valve being illustrated in the open position;

FIG. 9 is a perspective view from the bottom and left hand side of a valve in accordance with a second embodiment of the present invention, but with the second embodiment depicting ornamenteally the same valve design of the first embodiment but with additional color detail and markings in the drawings;

FIG. 10 is a front view of the valve shown in FIG. 9, with the valve being illustrated in the closed position;

FIG. 11 is a rear view of the valve shown in FIG. 9;

(Continued)

FIG. 12 is a left hand side view of the valve shown in FIG. 9;
FIG. 13 is a right hand side view of the valve shown in FIG. 9;
FIG. 14 is a top view of the valve shown in FIG. 9;
FIG. 15 is a bottom view of the valve shown in FIG. 9; and,
FIG. 16 is the same front view of the valve as shown in FIG. 10, except with the valve being illustrated in the open position.
The broken lines shown in the figures are included for the purpose of illustrating portions of the valve which form no part of the claimed design.
